(57) **CLAIM**

The ornamental design for a modular semi-hexadecagonal structure as shown and described.

DESCRIPTION

FIG. 1 is a top-front-left perspective view of a modular semi-hexadecagonal structure showing my new design; FIG. 2 is a bottom-rear-right perspective view thereof; FIG. 3 is a front elevational view thereof, the rear elevational view being mirrored thereto;

FIG. 4 is an enlarged left-side elevational view thereof, the right-side elevational view being mirrored thereto;

FIG. 5 is a top plan view thereof;

FIG. 6 is a bottom plan view thereof;

FIG. 7 is a top-front-left exploded view thereof;

FIG. 8 is a bottom-rear-right exploded view thereof;

FIG. 9 is a top-front-left perspective view thereof, wherein the modular semi-hexadecagonal structure supports an elongate overhead construction; and,

FIG. 10 is a bottom-rear-right perspective view thereof, wherein the modular semi-hexadecagonal structure supports an elongate overhead construction.

The broken line showing foundation walls, exterior paneling, panel reinforcements, purlin assemblies, and repeated iterations of the modular semi-hexadecagonal structure shown in FIGS. 9 and 10 is included for the purpose of illustrating environmental structure and forms no part of the claimed design.
